UNITED STATES PATENT OFFICE.

WILLIAM H. STOBIE, OF WATERVILLE, MAINE, ASSIGNOR TO HOLLINGSWORTH & WHITNEY COMPANY, OF BOSTON, MASSACHUSETTS, A CORPORATION OF MASSACHUSETTS.

APPARATUS FOR DISINTEGRATING FIBROUS MATERIAL.

1,182,432.

Specification of Letters Patent.

Patented May 9, 1916.

Application filed January 23, 1913, Serial No. 743,873. Renewed July 1, 1915. Serial No. 37,593.

To all whom it may concern:

Be it known that I, WILLIAM H. STOBIE, of Waterville, in the county of Kennebec and State of Maine, have invented certain 5 new and useful Improvements in Apparatus for Disintegrating Fibrous Material; and I do hereby declare the following to be a full, clear, and exact description of the invention, such as will enable others skilled in the art 10 to which it appertains to make and use the same.

My invention relates to an improvement in apparatus for disintegrating fibrous material, the object being rapidly and uniformly 15 to condition the fibers in a much shorter time, and at greatly reduced cost, than can be done under the processes or by apparatus now in use, and my improved apparatus may be used in a process wherein 20 the fibrous material is mixed with water and projected against a target.

My invention further consists in certain details as will be hereinafter more fully explained and pointed out in the claims.

25 The accompanying drawings show a view in elevation partly in section of one form of my improved apparatus.

A tank is represented at 1, having a target 2 therein. This target may be of any shape 30 and construction and is provided with a roughened or otherwise conditioned surface or surfaces against which the pulp stock is projected by the nozzles 5, three of which are shown. Leading from the bottom of the 35 tank 1 to the pump 6 is the pipe 7, and leading from the pump to the nozzles 5 is the pipe 8, the pipe 7 being preferably of larger diameter than the pipe 8 so as to provide for the necessary pressure in the latter. The 40 pipe 7 is provided with a throttle valve 11 by which the pressure of the pulp stock in the pipe 8 and nozzles 5 is regulated, and the pipe 8 is provided with a valve 12 by which the flow to the nozzles 5 may be cut 45 off.

Located within the tank 1 is an agitator 9 secured to a vertical shaft 10, which is provided at its upper end, preferably in a plane above the top of the tank 1, with a 50 bevel gear wheel 13, which meshes with a bevel pinion 14 on the driving shaft 15, the latter being coupled up to a motor or other source of power. This agitator is kept in motion while the pulp is being treated in

order to keep the latter thoroughly mixed 55 and in motion so as to prevent it from settling on the bottom of the tank at a point removed from the inlet to pipe 7.

Located in a plane above the tank 1 is the beater engine 16, in which the pulp stock is 60 partly shredded or disintegrated before it passes to the tank 1. After the stock has been treated in the engine 16 it is discharged through pipe 17 into tank 1. After the stock has been discharged into tank 1 the 65 agitator and pump may be started and the stock forced under high pressure by the pump, through the nozzles 5 against the target 2. The stock is unconfined after it leaves the nozzles, and hence is free to 70 spread out under the impact over the surface of the target and thus expose all the stock to the disintegrating action of the face of the target. The stock after contact with the target, falls back into the tank and is 75 acted upon by the agitator and again carried through the pump and nozzles to the target, and this operation is repeated until the desired condition of the stock has been attained. After the required condition of the 80 paper stock has been attained by repeated contact with the target, the valve 12 in pipe 8 may be closed and the valve 18 in pipe 19 opened. This pipe leads from pipe 8 at a point below valve 12 to the machine chest, 85 from which the pulp is pumped to the paper making machine, so that after treatment in tank 1, the pulp is forced by pump 6 and pipes 8 and 19 direct to the chest from which the paper making machine takes its pulp. 90 Located in the pipe 8 intermediate the pump 6 and the valve 12, is the chamber 20, within which is a diaphragm, and leading from one side of this diaphragm to the recording gage 21 is the small pipe 22. By means of this 95 arrangement, a continuous record may be obtained showing all pressures and variations of pressure within the pipe 8 during the entire treatment of the pulp, and also the length of time the pulp was under treatment. 100

Some mills that are running on approximately one grade all the time do not run the pulp over wet machines and press it to a certain percentage of dry weight and then weigh it out for the different grades of paper, and in such cases the beater engine 16 need not be used. 105

In using my invention less than one half the horse power needed by the old system is required, and one thousand pounds of stock for low grades of paper can be full treated 5 in ten minutes. Under the old system this is impossible unless the pulp be previously ground very fine, and even then without any reduction in horse power.

Again my invention enables the entire 10 process to be fully under the control of one man who receives instructions to run a certain grade of pulp under a certain pressure so many minutes, and he needs only to start with the proper pressure, and, watching the 15 chart on the gage, can operate the valves to maintain or change the pressure as may be necessary.

Under the old system from four to twelve 20 beaters are used, and as some may be dull and out of shape and others sharp, the product from the different beaters may vary. Again under the old system the operators 25 of the different machines may have different views as to how the pulp should be treated, and the extent of the treatment, but with my apparatus the resultant product is uniform.

It is evident that many slight changes 30 might be resorted to in the relative arrangement of parts shown and described without departing from the spirit and scope of my invention. Hence I would have it understood that I do not wish to confine myself 35 to the exact construction and arrangement of parts shown and described.

I claim:

1. The combination of a tank, a target

Copies of this patent may be obtained for five cents each, by addressing the "Commissioner of Patents, Washington, D.C."

having a roughened surface, a nozzle for projecting a stream of pulp against said target, a pump, a pipe leading from the 40 pump to the nozzle, pressure indicating means connected with said pipe, and pressure regulating means intermediate the vat and the nozzle whereby the pressure of the pulp stream passing to the target may be 45 regulated.

2. The combination of a tank, a target having a roughened surface, a pump, a pipe leading from the vat to the pump, a discharge pipe leading from the pump to the 50 nozzle, a pressure indicating means connected with said latter pipe, pressure regulating means intermediate the vat and the nozzle whereby the pressure of the pulp stream passing from the vat to the target 55 may be regulated, and a pipe connected with the discharge pipe intermediate the pump and the nozzle for directing the pulp away from the apparatus.

3. The combination of a tank, a target, 60 means for projecting a stream of pulp against said target, pressure indicating means connected therewith, and pressure regulating means whereby the pressure of the pulp stream passing to the target may be 65 regulated.

In testimony whereof, I have signed this specification in the presence of two subscribing witnesses.

WILLIAM H. STOBIE.
